(57) **CLAIM**

The ornamental design for a hydraulic pump roll frame handle, as shown and described.

DESCRIPTION

FIG. 1 is a front perspective view of a hydraulic pump roll frame handle showing our new design;

FIG. 2 is a top elevational view thereof;

FIG. 3 is a right side elevational view thereof;

FIG. 4 is a left side elevational view thereof;

FIG. 5 is a front elevational view thereof;

FIG. 6 is a rear elevational view thereof; and,

FIG. 7 is a cross sectional view thereof from the plane of the line 7-7 in FIG. 2.

The broken line representations of portions of the hydraulic pump roll frame in FIGS. 1-7 are shown for illustrative purposes only and form no part of the claimed design.
